Kain & Lewis,
Bedstead Fastening,
N°. 8076. Patented May 6, 1851.

UNITED STATES PATENT OFFICE.

JAS. R. KAIN AND SPENCER LEWIS, OF TIFFIN, OHIO.

BEDSTEAD-FASTENING.

Specification of Letters Patent No. 8,076, dated May 6, 1851.

To all whom it may concern:

Be it known that we, JAMES R. KAIN and SPENCER LEWIS, of Tiffin, in the county of Seneca and State of Ohio, have invented 5 certain new and useful Improvements in Bedstead-Fastenings; and we do hereby declare the following to be a full and clear description of the construction thereof, reference being had to the annexed drawings, 10 making part of this specification.

Figure 1 represents a vertical section of the post and cylindrical divided box and a section of the rail with its shank. Fig. 2 is a side view of the cylindrical divided box. 15 Fig. 3 is a section of the post, showing an end view of the divided box, with its wedge shaped wings. Fig. 4 is a perspective view of the upper section of the cylindrical box, showing the wedge shaped wings, and triangular projection. Fig. 5 is a perspective view of the shank of the rail, showing its wedge shaped wings and triangular projections. Fig. 6 is an end view of the rail 20 with its shank.

Where the same letters of reference occur on the several figures they indicate the same parts.

The nature of our invention and improvements consists in providing the upper section or part of the cylindrical box with two parallel wedge shaped wings and a triangular projection, on its periphery in such a manner that the triangular projection shall open a way or groove on its entrance into 30 the post, which shall be closed by the wedge shaped wings which are made to follow while the upper section of the box is being driven to its place in the bore of the post,— and thus crowd the wood in front of the 35 end of the triangular projection and form a complete lock to the cylindrical box, and prevent the possibility of its drawing out when once secured without tearing the wood with it.

My improvement also consists in dividing the cylindrical box longitudinally into two equal parts or sections, in such a manner that the upper section or part shall be made to serve the purpose of a wedge for forcing 40 the teeth projecting from the periphery of the lower section into the post.

My improvements further relate to the employment of parallel wedge shaped wings and triangular projections on opposing sides 45 of the shank of the rail for the purpose of

locking the same when driven into the rail for holding it securely.

A— is the post.

B— is the upper section or part of the cylindrical divided box. 30

C— is an inclined plane projecting from the inside of the upper section B.

D— is the triangular projection tapering from its base near the rear edge of the section B, upward, and frontward having its 65 edge sharp for cutting through the wood and forming a shoulder (a) at its front end which forms the lock.

E E are two parallel wedge shaped wings projecting about a quarter of an inch from the periphery and extending from the front edge of the section B, to the shoulder (a) of the triangular projection D— leaving a space between their adjacent sides equal to the thickness of said triangular projection, 70 and having their upper edges made sharp for passing into the wood and are for the purpose of crowding the wood between their adjacent sides which has the effect of closing the way, or groove previously made by 80 the entrance of the triangular projection D— and thus crowd the wood close against the shoulder (a) and forming a firm lock thereto.

F— is the lower section or part of the 85 cylindrical box, provided with an inclined plane (b) on its inner periphery for drawing the shank of the rail inward in connection with the inclined plane of the upper section B, to form a tight joint,—and also 90 provided with a series of teeth (c c). The inclined planes C, b, do not extend the full semi-diameter of the sections B, F, but leave spaces between their ends for the entrance of the shoulders or knobs (d) on the end 95 of the shank.

The cylindrical box is divided longitudinally into two equal parts or sections B, F, the line of division inclining upward at an angle of about 10 degrees from a horizontal 100 plane, so that in driving the upper section B into the bore of the post its edges will be made to act as wedges on the edges of the lower section F, and force its projecting teeth (c) into the wood and serve as a wedge 105 to hold it.

G— is a section of the rail.

H, is the shank provided on its end with shoulders or knobs (d) for passing over the inclined planes C, b, as the rail is turned 110

inward for drawing its shoulder close against the post.

I, I, are parallel wedge shaped wings projecting from the opposing sides of the shank, 5 H and having their upper and rear edges made sharp.

J, J, are the triangular projections situated in the rear and between the edges of the parallel wedge shaped wings I, I, and 10 made sharp for entering the rail,—the grooves or ways made by the entrance of which being closed by the entrance of the wedge shaped wings as they are driven in with the shank—and thus the shank cannot 15 be drawn therefrom without carrying the wood with it.

The post is bored in the usual manner and the lower section F of the box properly placed therein; the upper section B is then 20 inserted and with a mallet driven flush with the face of the post. The end of the rail is also bored and the shank H inserted and driven therein till the ends of the parallel wedge shaped wings I, I, are flush with the 25 face of the shoulder of the rail.

Having thus described our improvements on the bedstead fastening, what we claim therein as new and desire to secure by Letters Patent, is—

30 1. Providing the upper section or part B

of the cylindrical box with a triangular and two parallel wedge shaped wings D, E, E, made sharp and projecting from its periphery in such a manner that the triangular projection D, shall open a groove or way in 35 the post which shall be closed by the entrance of the parallel wedge shaped wings E, E, which follow, as the section B is driven into the post,—and thus crowd the wood in front of the shoulder (a) of the triangular 40 projection D, and for a complete lock thereto, as described.

2. We also claim dividing the cylindrical box longitudinally into two equal parts or sections B—F, the line of division inclining 45 upward at an angle of about 10 degrees from a horizontal plane, by which the edges of the upper section B are made to serve the purpose of wedges for forcing the teeth of the lower section F, into the post and 50 holding it securely as described.

In testimony whereof we have hereunto signed our names before two subscribing witnesses.

JAMES R. KAIN.
SPENCER LEWIS.
